UNITED STATES PATENT OFFICE

110,915

DESIGN FOR A COMBINED METAL BAND FILING AND SAWING MACHINE

Leighton A. Wilkie, Minneapolis, Minn.

Application January 17, 1938, Serial No. 74,356

Term of patent 3½ years

To all whom it may concern:

Be it known that I, Leighton A. Wilkie, a citizen of the United States of America and a resident of Minneapolis, county of Hennepin, and State of Minnesota, have invented a new, original, and ornamental Design for a Combined Metal Band Filing and Sawing Machine, of which the following is a specification, reference being had to the accompanying drawing, forming a part thereof, wherein

The figure is a perspective view of a combined metal band filing and sawing machine showing my new design, the opposite side of the machine is substantially the same as that shown except for the door.

What I claim is:—

The ornamental design for a combined metal band filing and sawing machine, substantially as shown and described.

LEIGHTON A. WILKIE.
